UNITED STATES PATENT OFFICE.

HENRY W. ROOS, OF CINCINNATI, OHIO.

LIFTING IMPLEMENT.

1,415,055.

Specification of Letters Patent. Patented May 9, 1922.

Original application filed March 14, 1919, Serial No. 282,602. Divided and this application filed December 14, 1920. Serial No. 420,682.

To all whom it may concern:

Be it known that I, HENRY W. ROOS, of Cincinnati, in the county of Hamilton and State of Ohio, have invented certain new 5 and useful Improvements in Lifting Implements; and I do hereby declare the following to be a full, clear, and exact description of the same, reference being had to the accompanying drawings, forming a part of 10 this specification, and to the reference-numerals marked thereon.

This invention has to do with lifting implements, and more particularly with such as are adapted for use with extensible stanchions or shores, the chief object of the invention being to provide a simple and inexpensive implement of this character which is practical in construction and efficient in operation, and adapted for use with the type 20 of shore disclosed in Letters Patent of the United States, No. 1,368,353, granted to me February 15, 1921, for adjustable shores, of which this application is a division. To these and other ends the invention consists 25 in certain improvements and combinations of parts all as will be hereafter more fully described, the novel features being pointed out in the claims at the end of the specification.

30 In the drawings:

Figure 1 is a side elevation of a lifting implement embodying the present invention, shown in working relation with a shore, parts being broken away.

35 Figure 2 is a top plan view of the implement as seen from the line 2^a—2^a of Figure 1.

Figure 3 is a view in elevation showing the type of shore with which the implement 40 is adapted to be employed.

Similar reference numerals throughout the several views indicate the same parts.

The embodiment of the invention herein disclosed by way of illustration of the principles involved and a preferred practical application thereof is capable, of course, of various modifications, being in the present instance particularly adapted for use with an adjustable shore of the type referred to 50 above, having relatively extensible parts, one of which embraces the other. The present device is adapted for detachable connection with one of these parts for engagement with the other to forcibly extend the same, as will 55 more fully appear from the following de-

tailed description. Referring more particularly to the drawings, the shore is shown as comprising a lower part or standard 10, preferably of metal tubing adapted to rest on the ground. The other extensible part 60 comprises spaced elements 11 extending on opposite sides of or embracing the part 10 in 65 sliding parallel relation therewith and connected at their upper ends by a block 12 for engagement with the object to be raised or sustained. The elements 11 have pivotally connected thereto adjacent their lower ends gripping yokes or jaws 13 which are pivotally connected with each other and arranged to grip or clamp the part 10 under 70 downward pressure of the elements 11 relative thereto. The latter have a slight movement toward and from each other to permit the operation of the gripping yoke, and a bolt 14 is passed through the elements 11 at 75 one side of the part 10 and provided with a nut 15 for drawing the elements together and insuring positive clamping action of the yoke after the shore has been adjusted. The upper end of part 10 carries a guiding head 80 16 slidable on the element 11, and the lower ends of the latter are preferably armored or protected by metal plates 17.

The implement or jack of the present invention is particularly adapted for use in 85 conjunction with a shore of the above type and comprises, preferably, a forked member 18 having spaced arms 19 arranged to clear the part 10 and to be brought under or in registry with the lower ends of the elements 11, the ends of the arms being preferably formed with curved or cam surfaces 90 20 for engagement with the lower ends of the elements as shown in Figure 1.

For supporting a second member 95 cooperating with the part 10 there is provided a spindle 21 bridging the arms 19 and having bearings at its ends therein, the spindle being held in place as by means of the cotter pins 22. Pivotally carried on spindle 21 is 100 a frame or member 23 having spaced bearing portions 24 engaging the spindle and a hook-like extension 25. Member 23 and its extension 25 are provided with opposed spaced bearing surfaces 26, preferably 105 rounded to conform with the tubular portion 10 and of substantial extent to prevent crushing of the latter. Both members 18 and 23 are substantially constructed to withstand the imposed stresses and to the same 110

end the arms 19 are preferably provided with web portions 27 over the bearings of spindle 21. A handle 28 is preferably provided in extension of the arm 19 of the 5 forked member, forming a lever for operating the implement.

In use, after the shore has been approximately adjusted with its tubular part 10 on the ground or other support, and with the 10 parts extended to bring block 12 against the object to be sustained, the hook-like extension 25 of the lifting implement or jack is engaged with the tubular part 10 with the cam surfaces 20 of arms 19 in engagement with the lower ends of the elements. By applying downward pressure to the handle 28 in this arrangement the upper extensible part is forced upwardly to apply supporting pressure to the object to be sustained or to elevate the latter as may be required. When the parts are extended, the yokes or jaws 13 tend to grip the part 10 and retain the shore in adjusted position, and such action of the yokes may be insured 25 by turning up the nut 15. The above described operation of the jack may, of course, be repeated as often as necessary to produce the desired extension of the shore, the hook 25 being readily slid along part 10 to successive positions of engagement, and when the adjustment is completed, the jack may be easily and quickly removed from the shore.

As indicated in the drawings, the lifting 35 implement or jack is simple and practical in construction and reliable and efficient in operation, being readily manipulated by a single operator and enabling him to bring to bear a very effective pressure.

40 I claim as my invention:

1. A jacking instrument for the relatively movable parts of an extensible shore comprising a pair of members pivotally connected with each other and each formed 45 for detachable engagement with one of said shore parts to effect relative movement thereof, and a handle portion on one of said members.

2. A jacking instrument for the relatively 50 movable parts of an extensible shore comprising a member formed for detachably gripping one of said shore parts to serve as a fulcrum, and a second member movably supported by said fulcrum member and 55 formed for detachable engagement with the other of said shore parts to effect relative movement of the latter.

3. A jacking instrument for the relatively 60 movable parts of an extensible shore comprising a gripping member for detachably gripping one of said shore parts to serve as a fulcrum, and a lever pivotally supported by said gripping member for de-

tachable engagement with the other of said shore parts to effect relative movement of 65 the latter.

4. A lifting implement for an adjustable shore having extensible parts, comprising a forked member provided with spaced arms adapted to engage one of said extensible 70 parts, a hook shaped member pivotally connected with said forked member and located between said arms for engagement with another of said parts, and handle means for operating the implement.

5. A lifting implement for an adjustable shore having extensible parts, comprising a forked member provided with spaced arms adapted to engage one of said extensible 75 parts, a spindle carried by said arms, a member pivotally carried by said spindle between said arms having a hook-like extension for engagement with the other of said parts, and handle means for operating said implement.

6. A lifting implement for an adjustable shore having extensible parts, comprising a forked member provided with spaced arms having cam surfaces adapted for engagement with one of said extensible parts, a 90 member pivotally connected with said forked member between said arms, a hook-like extension on said second member provided with opposed spaced bearing surfaces for engagement with another of said extensible parts, and handle means for operating 95 said implement.

7. A lifting implement for an adjustable shore having extensible parts, comprising a forked member provided with spaced arms 100 having cam surfaces adapted for engagement with one of said extensible parts, a spindle between said arms having bearings at its ends in the latter, a member pivotally carried by said spindle having a hook-like 105 extension provided with opposed spaced bearing surfaces for engagement with another of said extensible parts, and handle means for operating said implement.

8. A lifting implement for an adjustable 110 shore having a pair of extensible parts, one embracing the other, comprising a forked member having arms spaced to clear the inner and to register with the outer of said extensible parts, cam surfaces on said arms 115 for engagement with said outer part, a member pivotally carried on said forked member between said arms, a hook-like extension on said second member provided with curved bearing surfaces adapted for 120 detachable engagement with opposite sides of the inner of said extensible parts, and a handle on said forked member for operating the implement.

HENRY W. ROOS.
